DIGGER TOOTH FOR EXCAVATING APPARATUS

William W. Wilson, 6204 W. Canal Blvd., Shreveport, La.

Filed Mar. 9, 1964, Ser. No. 78,925

Term of patent 14 years

(Cl. D39—1)

FIG. 1 is a perspective view showing the new design for a digger tooth for excavating apparatus;

FIG. 2 is a side elevation of the tooth disclosed in FIG. 1;

FIG. 3 is a rear elevation thereof;

FIG. 4 is a front elevation thereof;

FIG. 5 is a section taken on line 5—5 of FIG. 1.

I claim:

The ornamental design for a digger tooth for excavating apparatus, as shown and described.
